US00D767137S

(12) United States Design Patent (10) Patent No.: US D767,137 S
(45) Date of Patent: * Sep. 20, 2016

(54) INTERVERTEBRAL IMPLANT

(71) Applicant: NuVasive, Inc., San Diego, CA (US)

(72) Inventor: Erika Lin, San Diego, CA (US)

(73) Assignee: NuVasive, Inc., San Diego, CA (US)

() Term: 15 Years

(21) Appl. No.: 29/547,760

(22) Filed: Dec. 7, 2015

Related U.S. Application Data

(63) Continuation of application No. 29/469,512, filed on Oct. 10, 2013, now Pat. No. Des. 745,159.

(51) LOC (10) Cl. 24-02

(52) U.S. Cl.

USPC D24/155

(57) CLAIM

The ornamental design for an intervertebral implant, substantially as shown and described.

DESCRIPTION

FIG. 1 is a perspective view of an intervertebral implant according to one embodiment of our new design; FIG. 2 is a front view of the intervertebral implant of FIG. 1;

FIG. 3 is a side view of the intervertebral implant of FIG. 1; FIG. 4 is a back view of the intervertebral implant of FIG. 1;

FIG. 5 is an top view of the intervertebral implant of FIG. 1;

FIG. 6 is an alternate side view of the intervertebral implant of FIG. 1;

FIG. 7 is a bottom view of the intervertebral implant of FIG. 1;

FIG. 8 is a perspective view of an intervertebral implant according to a second embodiment of our new design; FIG. 9 is a front view of the intervertebral implant of FIG. 8;

FIG. 10 is a side view of the intervertebral implant of FIG. 8;

FIG. 11 is a back view of the intervertebral implant of FIG. 8;

FIG. 12 is an top view of the intervertebral implant of FIG. 8;

FIG. 13 is an alternate side view of the intervertebral implant of FIG. 8;

FIG. 14 is a bottom view of the intervertebral implant of FIG. 8;

FIG. 15 is a perspective view of an intervertebral implant according to a third embodiment of our new design; FIG. 16 is a front view of the intervertebral implant of FIG. 15;

FIG. 17 is a side view of the intervertebral implant of FIG. 15;

FIG. 18 is a back view of the intervertebral implant of FIG. 15;

FIG. 19 is an top view of the intervertebral implant of FIG. 15;

FIG. 20 is an alternate side view of the intervertebral implant of FIG. 15; and,

FIG. 21 is a bottom view of the intervertebral implant of FIG. 15.

The broken line showing is included for the purpose of illustrating environment and forms no part of the claimed design.

1 Claim, 12 Drawing Sheets
